United States Patent Office.

WILLIAM H. MORGAN, OF ALLIANCE, OHIO, ASSIGNOR TO HIMSELF AND
RICHARD B. GEYER, OF ALLEGHENY, PENNSYLVANIA.

Letters Patent No. 107,087, dated September 6, 1870.

IMPROVED HARNESS-HOOK AND LOOP-SHIELD.

The Schedule referred to in these Letters Patent and making part of the same

To all whom it may concern:

Be it known that I, WILLIAM H. MORGAN, of Alliance, in the county of Stark and State of Ohio, have invented a new and useful Improvement in Harness-Hook and Loop-Shield Combined; and I do hereby declare that the following is a full and exact description thereof, reference being had to the accompanying drawing and to the letters of reference marked thereon.

The nature of my invention consists in a new article of manufacture, viz., a harness-hook and loop-shield combined, the same being constructed as hereinafter described.

To enable others skilled in the art to make and use my invention, I will proceed to describe more fully my new article of manufacture.

In the accompanying drawing, which forms part of my specification—

Figure 1 is a side view of my improvement in harness-hook and loop-shield combined.

Figure 2 is an edge view of the same.

Figure 3 is a longitudinal section of the same, when cut through at line *y* of fig. 1.

Figure 4 is a transverse section of the same, when cut through at line *y'* of fig. 1.

Figure 5 is a transverse section of the same, when cut through at line *y''* of fig. 1.

In the accompanying drawing—

A represents the harness-hook.

B and *B'* represent the openings for the strap or part of the harness to which it may be applied.

C represents the flange or projection used for hold-

ing the strap or part of the harness arranged on the hook.

D represents a strap or a part of the harness arranged on and in the hook.

e represents a tongue or partition between the openings *B* and *B'*.

f represents the opening or hook for the ring of the harness, which ring, in the drawing, is marked *R*.

The hook *A* may be cast of brass or other alloy, and plated to give it a fine finish, or it may be cast of "malleable iron," (cast-iron annealed,) and enameled, tinned, or plated, for the purpose of giving a fine finish to the hook.

The advantage of my new article of manufacture consists in adding strength and durability to that portion of the harness to which it may be applied.

Its advantage in its application to "bridle-reins," driving-reins, or lines and martingales, will be apparent to all manufacturers of harness.

Having thus described the nature, construction, and advantages of my new article of manufacture,

What I claim as of my invention is—

The harness-hook and loop-shield hereinbefore described, consisting of hook *A*, openings *B* and *B'*, tongue *e*, and flanges *C*, the whole being constructed and arranged as and for the purpose set forth.

W. H. MORGAN.
